UNITED STATES PATENT OFFICE.

MARTIN J. RYAN, OF NEW YORK, N. Y.

SASH-LOCK.

1,170,344.

Specification of Letters Patent.

Patented Feb. 1, 1916.

Application filed May 1, 1915. Serial No. 25,251.

To all whom it may concern:

Be it known that I, MARTIN J. RYAN, a citizen of the United States, residing at New York city, in the county of New York and state of New York, have invented new and useful Improvements in Sash-Locks, of which the following is a specification.

This invention relates to sash locks and it consists in the novel features hereinafter 10 described and claimed.

An object of the invention is to provide a lock of the character indicated adapted to be applied to the side rails of lower and upper sashes and having parts adapted to be 15 connected with each other in a manner to securely hold the sashes in fixed position with relation to each other and thereby prevent the sashes from being opened or moved even under the influence of a jimmy or other 20 powerful prying tool.

With the above objects in view the sash lock includes a plate which is applied to the side of the upper sash and which is provided with a series of internally threaded pockets 25 which are embedded in the rail of the sash. The lock also includes a member which is applied to the upper end of the side rail of the lower sash and which is provided with an opening through which a bolt may be in- 30 serted, the said bolt having a threaded end adapted to engage the thread of any one of the said pockets. The member which is applied to the lower sash is provided at its outer end with a plate which extends along 35 the outer surface of the side rail of the sash and securing devices pass through the said plate and coöperate with securing devices which pass through the upper portion of the said member and enter the side rail 40 of the sash and serve as means for securely holding the said member in position upon the sash. The said member is provided with outstanding lugs having openings, through which a securing pin may 45 be passed, the said pin also passing through the outer end of the bolt and serving as means for preventing the turning of the bolt after it has been secured in position in the parts of the lock.

50 The parts of the sash lock may be modified whereby two or more securing bolts may be employed, if desired, and the said lugs may be provided with openings for holding the bolt, or bolts, when the same are

not in use, as means for connecting the parts 55 of the lock together.

In the accompanying drawing:—Figure 1 is a side elevation of portions of window sash with the lock applied. Fig. 2 is an enlarged sectional view of the same. Fig. 3 60 is a top plan view of the member of the lock which is applied to the lower sash. Fig. 4 is a plan view of the bolt which is a part of the lock.

As illustrated in the accompanying drawing the sash lock includes a plate 1 adapted to be applied to the side rail of the upper sash and having internally threaded pockets 2 which are embedded in the said side rail. The said plate 1 may be secured by screws 3 70 or other suitable securing devices.

A member 4 is positioned upon the upper edge of the lower sash at the upper end of the side rail thereof, and the said member is provided with openings 5 through which 75 screws or other suitable securing devices may be passed for holding the member in proper position upon the sash. A barrel portion 6 is provided upon the member 4 and the said barrel is open from end to end. The barrel 80 6 is disposed transversely across the lower sash when the member 4 is applied thereto. The member 4 is provided at the outer edge of its body portion with a depending flange 7 which extends along the face, or side of 85 the lower sash, and a screw 8, or other suitable securing device, passes transversely through the plate 7 and enters the side rail of the sash. The screw 8 serves in combination with the devices which pass through the 90 opening side as means for effectually holding the member 4 in position upon the sash. Spaced lugs 9 extend outwardly from the plate 7 and are provided with openings 10. The said flanges may be further provided 95 with openings 11. A bolt 12 is adapted to be passed through the barrel 6 and the said bolt is provided at one end with a thread 13 which is adapted to engage the thread in any one of the pockets 2. The bolt 12 is provided at its outer end with a head 14 having an opening 15. A pin 16 is insertible through the opening 15 and the openings 10 in the lugs 9 and when in position as shown in Fig. 2 of the drawing, serves as means 100 for holding the bolt 12 against turning movement. The lower sash may be provided with a bore 17 which at its outer end com-

5 municates with an opening 18 provided in the plate 7 and the said bore and opening may receive a bolt similar to the bolt 12 and the thread of the last mentioned bolt may be engaged with the thread of any one of the pockets 2, consequently two or more bolts may be used in conjunction with the other parts of the lock as desired.

10 The parts of the lock are secured together in the following manner: Assuming that the upper and lower sash have been adjusted to such positions in the frame as are desired, and when a single bolt 12 is used the said bolt is passed through the barrel 6 and is 15 rotated therein so that its threaded end 13 engages in the thread of one of the pockets 2. When the bolt has been moved in an inward direction to such an extent that its head 14 is in contact with the outer end of 20 the barrel, or approximately so, the opening 15 in the head is brought into vertical register or alinement with the openings 10 in the lugs 9. The pin 16 is then inserted down through the said openings and the bolt 12 is 25 held against turning movement. Consequently the parts of the lock are securely and effectively held together. In the event that a second bolt is used, it is passed through the bore 16 and engaged with the 30 pocket of the plate 1 as above described and the pin 16 is passed through the opening 15 of the head of the second mentioned bolt. Thus, a single pin may be employed for holding a series of bolts against turning 35 movement when the lock is applied. To release the sashes from each other, the pin 16 is withdrawn from the bolt, and the lugs and the said bolts or bolt are then unscrewed from the pockets or pocket, and 40 are removed from the barrel 6 and the bore 17 in the event that two bolts are used. When a single bolt is used in conjunction with the other parts of the lock and it is removed from the barrel, it may be inserted 45 through the openings 11 in the lugs 9 and

thus the said bolt is retained at the lock structure and is ready at hand for application when desired.

From the above description taken in conjunction with the accompanying drawing, it will be seen that a sash lock of simple and durable structure is provided and that when the parts of the lock are secured together, the sashes are effectually held against movement with relation to each other and the presence of the securing devices through the plate 7 of the member 4 will hold the sash in position against the prying action of a jimmy or other tool, inasmuch as it is necessary to shear the heads of the securing devices from the bodies thereof, or break the said devices in order to effect a separation of the lower sash from the said plate 7.

Having described the invention what is claimed is:—

65 A sash lock comprising a plate having at one side pockets which are embedded in one sash, another plate having a barrel resting on the top of the other sash and provided with a depending flange which extends along 70 the side of the sash and disposed at a right angle to said barrel, securing devices passing through the flange and entering the sash at the side thereof, a bolt extending through the barrel and having a threaded end adapted 75 to engage the thread of one of the pockets, said bolt having an enlarged head adapted to engage the flange whereby the sashes may be drawn together, there being provided upon the said flange an outstanding lug, 80 said lug and the bolt having openings and a key insertible through the openings of the bolt and the lug to hold the bolt in locked position.

85 In testimony whereof I affix my signature in presence of two witnesses.

MARTIN J. RYAN.
